UNITED STATES PATENT OFFICE

160,501

REFRIGERATOR

William E. Jones, Medford, Mass.

Application April 17, 1948, Serial No. 145,786

Term of patent 3½ years

(Cl. D80—11)

To all whom it may concern:

Be it known that I, William E. Jones, a citizen of the United States, residing at Medford, in the county of Middlesex and Commonwealth of Massachusetts, have invented a new, original, and ornamental Design for Refrigerator, of which the following is a specification, reference being had to the accompanying drawings, forming part thereof.

Fig. 1 is a front perspective view of a refrigerator, showing my new design.

Fig. 2 is a rear perspective view of the refrigerator shown in Fig. 1.

I claim:

The ornamental design for a refrigerator, substantially as shown.

WILLIAM E. JONES.
